CLOSURE MEANS FOR CONTAINER FILLING
OPENINGS

George R. Godber, Los Angeles, Calif.

Application May 22, 1944, Serial No. 536,856

6 Claims. (Cl. 136—178)

This invention relates to closure means for the filling openings of containers such as electric storage batteries, and has particular reference to improvements in closure means of the general type described and claimed in my prior patents, Nos. 2,242,671 and 2,242,672 of May 20, 1941, to predetermine the level to which containers such as electric storage batteries and the like may be filled with liquid.

Generally speaking, the object of the invention is to provide a closure means which includes a lesser number of parts and which is cheaper and easier to manufacture and assemble than the closure means described and claimed in my aforesaid prior patents, and which, at the same time, is thoroughly reliable and efficient in the performance of its function of predetermining the level to which containers such as storage batteries and the like may be filled with electrolyte or other liquid.

With the foregoing general object in view, the invention consists in a closure means embodying the novel features of construction, combination and arrangement of parts as will be hereinafter more fully described, illustrated in the accompanying drawing and defined in the appended claims.

In the accompanying drawing, wherein like characters of reference denote corresponding parts in the different views:

Figure 1 is a vertical section through the top portion of an electric storage battery equipped with a closure means constructed in accordance with the invention, the closure cap being shown removed and the liquid-level-control-sleeve being shown in the lower position it assumes when the closure cap is removed.

Figure 2 is a view similar to Figure 1 showing the closure cap applied and the liquid-level-control-sleeve in its upper position.

Figure 3 is a plan view of the closure means with the closure cap removed; and

Figure 4 is a side elevation of the liquid-level-control-sleeve.

Referring to the drawing in detail, A designates a portion of a container, such as an electric storage battery, having a top wall 10 provided with a filling opening 11, B designates a removable closure cap for said filling opening 11, and C designates a liquid-level-control-sleeve associated with said filling opening and itself controlled by said closure cap B.

A lower portion of the filling opening 11 is formed of lesser diameter than the portion there-

above to provide in said filling opening an upwardly facing, annular shoulder 12. The sleeve C is disposed in the filling opening 11, coaxially therewith, and its lower portion, 5 which extends through the lower portion of said filling opening is of an external diameter slightly less than the said lower portion of said filling opening for free vertical sliding movement therethrough. On the other hand, an upper portion of 10 said sleeve, which is disposed in the upper portion of said filling opening 11, is of slightly lesser external diameter than the said upper portion of said filling opening for free vertical sliding movement therein, but is of greater external diameter 15 than the lower portion of said filling opening to provide a downwardly facing, exterior annular shoulder 13 on said sleeve for engagement with the shoulder 12 to limit downward movement of said sleeve in said filling opening and also to 20 provide a seal to prevent escape of air from the container A through said filling opening exteriorly of said sleeve.

As shown, the shoulder 12 may appropriately be provided by forming an inwardly extending 25 annular flange 14 on the wall 15 surrounding and defining the filling opening 11 at or near the lower end of said wall, while the shoulder 13 may appropriately be provided by forming an exterior annular flange 16 on the sleeve C at or near the 30 upper end of said sleeve. In any event, the sleeve C is freely movable vertically in the filling opening 11 between a lower, operative position as shown in Figure 1 and an upper, inoperative position as shown in Figure 2, and is provided with 35 suitable stop means for cooperation with suitable stop means carried by the wall 15 surrounding and defining the opening 11 to limit its downward movement in the filling opening and to provide an air seal to prevent escape of air around the exterior thereof through said filling opening when 40 it is in its lowermost position in said filling opening. Moreover, suitable means is provided to prevent rotation of said sleeve C, this means comprising, for example, a lug or lugs 17 on said sleeve, 45 exteriorly thereof engaged in a vertical channel or channels 18 in the wall 15 or, if desired, a lug or lugs on the wall 15 engaged in a vertical channel or channels in said sleeve.

The closure cap B is screw-threaded, as indicated at 19, for screw-threaded engagement with screw-threads 20 at the upper end of the wall 15, and in this connection the threads 19 may be of the exterior or male type and the threads 20 may be of the interior or female type, as shown, or, 50 if desired, the threads 19 may be of the female

type and the threads 20 may be of the male type. In any event, the sleeve C is provided with interior threads 21 and the closure cap B is provided with a central, depending plug 22 having exterior threads 23 for cooperation with said interior threads 21. Moreover, the relationship of the parts is such that, upon removal of the closure cap B, the threads 21 become disengaged from the threads 23 prior to disengagement of the threads 19 from the threads 20, thus to insure against the undesirable possibility of the sleeve C remaining engaged with the plug 22 and being removed with the closure cap B.

When the closure cap B is removed and sleeve C thereby is released, said sleeve gravitates to its lowermost position as determined by engagement of its shoulder 13 with the shoulder 12, and in this position of said sleeve, as shown in Figure 1, the lower end thereof is disposed a predetermined distance below the top wall 10 of the container A. Also, engagement of the shoulder 13 with the shoulder 12 provides a seal preventing escape of air from the container A around the outside of the sleeve C. The container then may be supplied with liquid through the sleeve C until the level of the liquid in the container rises to and closes the bottom of said sleeve, whereupon any further supply of liquid to the container will be prevented by the air confined in the upper portion of the container. Over-filling of the container thus is prevented and the height to which it may be filled may be pre-determined by pre-determining the length of the sleeve C so that the lower end thereof will be disposed at a given level when said sleeve is in its lowermost position.

When the container A has been filled to the permissible level as determined by the sleeve C, any further attempt to supply liquid to the container simply will result in the liquid filling or partly filling said sleeve C and the opening 11 and this will serve to indicate that more liquid cannot be supplied to the container.

The threads 21, 23 are synchronized with the threads 19, 21 so that when applying the closure cap B, free, non-binding engagement of the threads 21 with the threads 23 is insured and occurs either simultaneously with, or soon after, engagement of the threads 19 with the threads 20. Moreover, the threads 21, 23 are of greater pitch than the threads 19, 20. Consequently, as the closure cap is screwed to its closed position, the sleeve C is lifted and thereby the top portion of the container is vented so that any liquid contained in said sleeve and the filling opening 11 is permitted to flow into the container. However, the amount of liquid which may be contained in the sleeve C and the filling opening 11 is so small as negligibly to affect the level of the liquid in the container. In the case of an electric storage battery, the sleeve C is of length to predetermine filling of the battery container to, but not above, a desired level above the tops of the battery plates 24 so as to leave an air or gas space of desired height in the top of the container above the level of the electrolyte therein.

The plug 22 is hollow and is open at its lower end and communicates at its upper end with a vent opening 25 in the top of the closure cap B to permit escape of gas from the container A when said closure cap is in its applied position closing the filling opening 11 as shown in Figure 2. Moreover, a disk 26 which may be flexed to be inserted in the plug 22 and then released to be frictionally retained in said plug, preferably is provided to intercept any splash of the liquid in

the container A and thus prevent escape of the liquid through the vent opening 25, the said disk 26 having, however, a marginal recess or recesses to permit escape of gas from the container.

The threads 21, 23 may be of either the single type or the double type as shown.

As will be apparent from the foregoing, the present closure means embodies only two main elements apart from the container; viz., the closure cap B and the sleeve C. As will be equally apparent, these two main elements are capable of economical manufacture and the element C always is free when the closure cap B is removed, to be removed from and to be replaced in the filling opening 11, which is of very material advantage in expediting filling and emptying of the container of weak preliminary or formative charges of electrolyte preparatory to supplying the same with its final, strong charge of electrolyte.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. Closure means for the filling opening of a container comprising a threaded sleeve disposed vertically in said opening and freely movable vertically therein, means holding said sleeve against rotation, a closure cap for said opening having threaded engagement with the container, a plug depending from said closure cap and having threaded engagement with said sleeve, the threads of said closure cap and said container being related to the threads of said sleeve and said plug so that when the closure cap is removed the plug threads become disengaged from the sleeve threads prior to disengagement of the closure cap threads from the container threads and so that when the closure cap is applied its threads engage the container threads prior to engagement of the plug threads with the sleeve threads, stop means to limit downward movement of the sleeve when the same is released by removal of the closure cap and to provide a seal to prevent escape of air from the container around the outside of the sleeve, said sleeve depending a predetermined distance into the container when it is at its limit of downward movement, and said plug and sleeve threads being of greater pitch than the closure cap and container threads so that when the closure cap is applied the sleeve is lifted.

2. Closure means as set forth in claim 1 in which the sleeve is provided with interior threads and the plug is provided with exterior threads.

3. Closure means as set forth in claim 1 in which the closure cap and container threads are synchronized with the plug and sleeve threads to insure free, non-binding engagement of the latter threads with each other when the closure cap is threaded onto the container.

4. Closure means as set forth in claim 1 in which the sleeve is free to be removed from and to be replaced in the filling opening when the closure cap is removed.

5. Closure means as set forth in claim 1 in which the sleeve is provided with an annular external flange and in which the lower portion of the filling opening is of lesser diameter than the

upper portion of said opening to provide an upwardly facing shoulder to be engaged by said flange to limit downward movement of the sleeve and to provide the seal to prevent escape of air from the container around the outside of the 5 sleeve when the closure cap is removed.

6. Closure means as set forth in claim 1, in

which the means holding the sleeve against rotation comprises a lug on one of said sleeve and the wall surrounding the filling opening engaged in a vertical channel in the other of said sleeve and said wall.

GEO. R. GODBER.
